UNITED STATES PATENT OFFICE

LEO P. KELLER, OF COLUMBUS, OHIO

ACCESSORY FOR VACUUM CLEANERS

Application filed October 11, 1927. Serial No. 225,530.

This invention relates to an accessory in the nature of an attachment for vacuum cleaners, suction cleaners, suction sweepers, household air cleaners, and the like, where-
5 by the implement, in addition to its function as a cleaning implement, is converted into a sanitary implement for the purpose of utilizing the suction or blower effect of the cleaner as a disseminator for a germi-
10 cide.

Vacuum cleaners as cleaning implements utilize a blower pressure as suction to draw dirt and refuse through the cleaner and into a bag in which the dirt accumulates, or utilize the blower pressure of the cleaner as a blower for blowing dust or dirt from articles to be cleaned. In both uses, it is the moving power of the air which serves the cleaning effect, and the present invention 20 aims to take advantage of this blowing power by providing an accessory which may be readily connected to the vacuum cleaner and which arranges in the path of the air, either on the suction side or blower side of the 25 cleaner, a receptacle containing a germicide through which the air is directed, so that said germicide will be drawn into and through the article being cleaned when used in connection with the suction side of the 30 cleaner or may be blown into contact with an article to be treated when using the blower side of the cleaner.

The invention, more specifically stated, comprises a container which may be readily 35 connected to the suction side of the cleaner or to a receptacle connected to the suction side of the cleaner, or as readily connected in the line on the blower side of the cleaner to force the germicide-laden air to any point 40 of application.

The invention is illustrated in the accom-
panying drawings, in which:

Figure 1 is a broken perspective view 45 showing a particular type of vacuum cleaner with the improved accessory arranged on the blower side thereof.

Figure 2 is an enlarged longitudinal sec-
tion through the germicide container with 50 the flexible connectors by which it may be connected to the vacuum cleaner.

Figure 3 is an elevation, partly in sec-
tion, of a particular type of flexible con-
nector, adapting the accessory for convenient
use with substantially all types of vacuum
cleaners.

Figure 4 is a view in elevation of a pipe
connection through which the germicide-
laden air may be directed in contact with any
object.

The vacuum cleaner illustrated in the
drawings is intended to represent any type
of such well known implement in which, as
is understood, a current of air is drawn
through the suction inlet 1 and delivered
through the blower outlet 2. Ordinarily, the
suction inlet is connected with an appropri-
ate implement to be passed over the sur-
face to be subjected to the suction and the
blower outlet 2 is removably connected to a
bag in which the dust and dirt drawn into
and through the vacuum cleaner is deposited.

The present invention is directed more
particularly to a germicide container pro-
viding a complete unit and capable of being
connected in the suction line or blower line
of the vacuum cleaner. The container com-
prises a hollow casing 3 reduced at one end
to form a conical nozzle 4 and freely open
at the opposite end. A foraminous cage 5
having an open end 6 is provided with a 80
lateral flange 7 which overlies the free edge
of the casing 3. The cage is of frusto-coni-
cal formation, that is, its annular wall is
convergent from the flange 7 so that its inner
closed wall 8 is of less diameter than the 85
mouth of the casing 3. Due to this con-
vergence and the perforated condition of the
annular wall and inner wall 8, the air forced
through from the closed end of the cage can
readily enter throughout the full length of 90
the cage, but of course must pass through
the cage in order to find an outlet.

The container includes a cap 9 having a
conical nozzle 10 and an annular flange 11
which fits over the end of the casing 3 and
is more or less tightly held in connection
therewith by the pin and slot connection
illustrated at 12. The wall 11 of the cover
is formed to provide a shoulder 13 which,
when the cover is in applied position, bears 100

upon the flange 7 of the cage 5 and securely, though removably, fixes the cage in position. The cover is provided in line with the shoulder 13 with a partition 14 perforated at 15 which, when the cover is applied, forms a perforated closure for the cage, as clearly shown in Figure 2.

It will of course be understood that all vacuum cleaners are provided with certain accessories, such as a hose connection illustrated at 16 in Figure 4 and a series of nozzles 17 of different types to be connected at one end of said hose connection. Ordinarily, the hose connection is to be removably connected to the blower outlet 2 of the vacuum cleaner following the disconnection of the usual refuse bag, so that air blown through the cleaner may be directed in contact with various objects, such as a wall, 20 mattress, or like surfaces. In the use of the improved germicide receptacle, such accessory is to be interposed in the blower line between the blower outlet 2 and the hose 16 or between hose 16 and nozzle 17, and for 25 this purpose flexible connectors 18 and 19 may be applied to the respective nozzles 4 and 10 of the accessory, the connectors, either or both, being in turn connected to the blower outlet 2 of the vacuum cleaner 30 and the connector 19 joined to the hose 16.

In some instances, it may be found that the terminal of the hose 16 will directly engage the nozzle 10, and in other instances it will be found that the terminal of the hose 35 is in the type of a metallic connector adapted to interlock with a particular configuration on the blower outlet 2. Under these circumstances, the connectors 18 and 19 are particularly formed at the ends which connect with the hose and with the blower outlet 2 to provide a tight connection notwithstanding the particular interlocking formation. To secure this result, the connectors 40 18 and 19, either or both, may be formed at 45 both ends with an inturned margin 20 providing a comparatively small opening 21. When this connector is forced over the blower outlet or hose terminal, the flanged end will yield to compensate for the interlocking formation while at the same time providing the desired tight connection.

It has been heretofore proposed to provide a comparatively large flexible bag-like enclosure adapted to be removably connected to the suction end 1 of the vacuum cleaner, in which bag-like enclosure articles such as clothing, pillows, and other small articles may be placed, in order that in the operation of the vacuum cleaner, the air may 55 be drawn over and through the contained articles to remove dust and dirt therefrom. It is designed to use the improved accessory with such containers, as in such use the mouth of the bag, that is the opening remote 60 from the suction end 1 of the vacuum

cleaner, is drawn more or less tightly around the casing 3, so that all air entering the bag must pass through the casing and cage 5.

In use, the cage 5 is designed to be charged with a loose carrier, as a sponge, cotton batting, or the like as indicated at 22, and an appropriate amount of germicide, insecticide, deodorizer, or if desired ordinary perfume, is poured into the carrier 22 and the cover 9 applied. With the accessory connected in the blower end of the vacuum cleaner, all air delivered by the power of the motor of the cleaner is compelled to travel through the cage and through the carrier charged with the fluid. Such air then leaves the cover nozzle 10 charged with the vapor or volatile constituents of the particular liquid used and may be delivered at any point or into any surface or directed generally into the air. Owing to the large pressure capacity of the usual vacuum cleaner, it will be apparent that a very considerable portion of the volatile constituents of the liquid will be picked up and directed with material force into the surface or into the article being treated. There is thus provided a means by which a germicide-laden air may be utilized effectively with little labor and loss of time as an effective insect destroyer. In this connection, the use of the accessory provides a simple, effective and readily controlled destroyer for moths and moth larvae. The walls of a sick room may be treated or the general air of a room may be deodorized, 100 fumigated, or even perfumed in a simple and expeditious manner by merely arranging the accessory in the blower end or outlet of the vacuum cleaner and operating the latter.

In the use of the accessory in connection with the article-containing bag hereinbefore referred to, it is apparent that the articles in the bag are not only subjected to the cleansing action of the air passing therethrough, but may be at the same time treated with any desired germicide or insecticide which not only cleans such articles but will also thoroughly destroy any germ, insect or larva life which may be present. For example, this particular use provides a very convenient, simple and expeditious manner of not only removing dust and dirt from articles of clothing, but at the same time destroying any moths or moth larvae which may be present.

It is of course to be understood that the invention, while more particularly directed to the specific construction of the germicide container, is also directed to the use of such container in connection with any type of power-driven vacuum cleaner.

This cleaner accessory or spraying device is designed especially in the interests of health protection and for the reconstruction

of germ-laden and malodorous air in public places, for destroying exhaled breath germs and perfuming the air, being particularly useful in those places which, by reason of 5 their use and character, are used by a large number of people, such for example as passenger trains and the like.

The invention is also particularly effective for destroying germs in the interior of 10 rooms, such as hotel rooms, and is of course more particularly directed to the mattresses and bedding as well as the walls of such rooms. Hotel guests are of course not subjected to medical examination and the bedding 15 used by one guest, that is, the mattress and pillows, are, after a mere change of bedding, as sheets and pillow-cases, used by the next guest. The present invention provides a means in which the mattress and pillows 20 as well as the walls may, in a most efficient and expeditious manner, be thoroughly treated to avoid any lack of perfect cleanliness in this particular and insure practically a complete sanitary cleaning for the perfect 25 security of the next occupant.

What I claim to be new is:

An accessory for vacuum cleaners, including a cylindrical body open at one end and with a reduced extension at the opposite end, 30 a foraminous cage of convergent form having an edge flange to overlie and bear on the edge of the open end of the body, a cap threaded on said open end of the body and bearing on and securing the cage in place, 35 said cap having an extension corresponding in size and form to that of the body, and a foraminous plate secured in and carried by the cap, and forming a cover section for the cage when the cap is in place.

In testimony whereof I affix my signature.
LEO P. KELLER.
